US0D1075280S

(12) **United States Design Patent** (10) **Patent No.:** **US D1,075,280 S**
(45) **Date of Patent:** **** May 20, 2025**

(54) **CUP COVER**

(71) Applicant: **Xixian Cao**, Changsha (CN)

(72) Inventor: **Xixian Cao**, Changsha (CN)

(**) Term: **15 Years**

(21) Appl. No.: **29/942,292**

(22) Filed: **May 14, 2024**

Related U.S. Application Data

(63) Continuation of application No. 29/908,330, filed on Jan. 11, 2024, now Pat. No. Des. 1,026,446.

Primary Examiner — Steven J Czyz

(57) **CLAIM**

The ornamental design for a cup cover, as shown and described.

DESCRIPTION

FIG. 1 is a front, top perspective view of a cup cover, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the cup cover, shown in an environment of use; and,

FIG. 10 is another perspective view of the cup cover, shown in an environment of use.

The evenly dashed broken lines are shown for the purpose of illustrating both parts of the cup cover as well as environmental subject matter. None of the broken lines form part of the claimed design.

1 Claim, 10 Drawing Sheets

US D1,075,280 S
